UNITED STATES PATENT OFFICE.

FRANKLIN G. NEUBERTH, OF ANSONIA, CONNECTICUT.

MACHINE FOR MAKING BUTTON-FASTENERS.

1,128,352.

Specification of Letters Patent. Patented Feb. 16, 1915.

Application filed April 13, 1912. Serial No. 690,474.

To all whom it may concern:

Be it known that I, FRANKLIN G. NEUBERTH, a citizen of the United States, residing at Ansonia, in the county of New Haven and State of Connecticut, have invented certain Improvements in Machines for Making Button-Fasteners, of which the following description, in connection with the accompanying drawings, is a specification, like reference characters on the drawings indicating like parts in the several figures.

This invention relates to improvements in machines for making wire fasteners such as the shank of a button and is herein shown as embodied in a machine for making a shank for use in the metal button disclosed in my co-pending application Serial No. 659,523, filed November 10, 1911. The shank of that button comprises a substantially circular loop or eye with feet extending outwardly from the lower side of the eye and in the plane of the eye, the outer ends of the feet being bent in opposite directions out of the plane of the eye and preferably curved to correspond to the curvature of the button head.

One object of the present invention is to provide automatic mechanism for producing a shank of this description, although the invention is not limited in its application to the production of a fastener of this or any other particular style. In the manufacture of such articles it is customary to employ a series of bending tools which are operated in the proper timed relation for shaping a piece of wire into the required form.

An important feature of the present invention consists in the provision of a tool holder in which the bending tools are mounted and a single cam disk arranged to surround the tool holder and having separate cam faces which operate on the tools when the cam disk and tool holder are relatively turned. Such a construction presents the advantages of simplicity and compactness and may be embodied to a good advantage in automatic machinery for constructing the entire button.

Another important feature of the invention relates to the devices by which the outer ends of the feet of the shank are bent out of the plane of the eye and given their characteristic shape. As herein shown this result is effected by providing means for clamping the inner part of the feet of the

shank and a twisting tool arranged to engage the outer ends of the feet and bend them simultaneously in opposite directions.

In the preferred embodiment of the invention the bending tools operate first to form the eye of the shank with feet extending oppositely in alinement and these same tools serve to clamp the inner part of the feet while the twisting tool operates to bend their outer ends.

These and other features of the invention will be best understood and appreciated from the following description of a preferred embodiment thereof selected for purposes of illustration and shown in the accompanying drawings, in which—

Figure 1 is a plan view of mechanism embodying my invention having parts of the tool retracting ring broken away; Fig. 2 is a fragmentary plan view showing the bending tools in the position which they occupy at the conclusion of the first step in bending the eye; Fig. 3 is a similar view showing the tools in the position which they occupy after the side bending tools have begun to act; Fig. 4 is a similar view showing the tools in the position they occupy at the conclusion of the operation of the side bending tools; Figs. 5 and 6 are perspective views respectively of the concave bending tool and one of the side bending tools; Figs. 7 and 8 are views in perspective of the bending and shank end twisting tool in two different positions, and Fig. 9 is a view in perspective on an enlarged scale of one of the completed shanks.

The operation of the mechanism shown in the drawings will be more easily followed if the shape of the finished shank is first considered. As shown in Fig. 9, the shank comprises an eye 3 of substantially circular shape which merges at its lower side into a short stem 5. The wire of the stem is bent in opposite directions forming the feet 7 which lie in the plane of the eye and in alinement with each other. The outer ends 9 of the feet are bent in opposite directions in a plane at right angles to the plane of the eye and are curved about a center approximately coinciding with the axis of the eye 3.

The tool holder 6 comprises a disk having radially extending guideways formed in its surface and a centrally disposed former 1 about which the wire is bent in forming the eye of a shank. In each of the guideways is mounted one of a series of four

bending tools of which the first to operate comprises the bending tool 8 having its inner end concave in circular cross section to coöperate with the stationary former 4. As shown in Fig. 5, the edges of the concave face are notched to receive the wire to be bent and to locate it properly in vertical position. The outer end of the tool 8 is beveled to coöperate with the cam surface 16 formed in the inner edge of the actuating disk 2 which is arranged concentrically about the tool carrier 6. Movement of the actuating disk 2 in the direction of the arrow, Fig. 1, advances the tool 8 toward the former with the result that the wire which has previously been introduced between the tool and the former is partially bent into the shape shown in Fig. 2, that is, with its center portion curved about the former 4 and its ends extending at an angle somewhat less than 90° with each other.

The tools next operated are the side bending tools 10 and 12 which are of similar character and comprise a curved portion 26 which supplements the curved portion of the tool 8 and oppositely disposed projecting portions which form the stem of the eye. Upon the side opposite to the bending tool 8 the side bending tools are notched in order 30 to receive the outwardly extending feet of the shank as will be explained hereinafter. The outer ends of the side bending tools 10 and 12 are beveled to coöperate with the cam surfaces 18 and 20 formed in the edge of the 35 actuating disk 2. The result effected by the operation of the side-bending tools is indicated in Figs. 3 and 4 from which it will be seen that their projecting ends first engage the outer side of the partially bent wire and 40 in their advancing movement bend the wire completely about the former 4 leaving its ends projecting outwardly at an obtuse angle in the notches in the back of the bending tools.

The tool next operated is that which bends the feet of the shank into alignment with each other and comprises a spindle 22 set in the block 14 and having a slotted end adapted to receive the feet of the shank. Surrounding the spindle 22 is a sleeve 24 having segmental shoulders 26 and 28 formed on its end which extend flush with the spindle end. The sleeve is also provided with a handle 25 by which it may be partially rotated. The outer end of the block 14 is beveled to coöperate with a cam surface 15 formed in the edge of the actuating disk 2 and in the continuous rotation of the disk 2 after the side bending tools 10 and 12 have been advanced to position shown in Fig. 4 the cam surface 15 will act upon the block 14 and advance the spindle 22 which receives the ends of the wire in its slot and bends them in opposite directions substantially at right angles to the stem of the shank.

The shank is completed by bending the outer ends of its feet so that they extend in a plane at right angles to the plane of the eye and this is effected by turning the sleeve 24. In the initial position of the sleeve 24 the shoulder 26 is located above the projecting end of one of the feet of the eye while the shoulder 28 is located beneath the end of the other foot, the center of the inner portion of each foot being rigidly held 75 in the slot in the spindle 22 and clamped against the side bending tools 10 and 12. When the sleeve 24 is turned from the position shown in Fig. 7 into that shown in Fig. 8 the ends of the feet which extend beyond the spindle 22 are bent in opposite directions about the cylindrical surface of the end of the spindle and a finished eye of the nature shown in Fig. 9 is produced.

When the shank has been completed the 85 actuating disk 2 is turned in the direction opposite to that indicated by the arrow in Fig. 1 and the bending tools are moved outwardly to their initial position. This reverse movement may be effected in any desired manner but as shown herein, each of the bending tools is provided with a cam pin 30 which engages a cam slot of suitable shape in a ring 32 secured to the surface of the actuating disk 2.

Any convenient means may be utilized for turning the twisting sleeve 24. For purposes of illustration there is shown merely the handle 25 which it will be apparent may be connected to any automatic actuating 100 mechanism. It will also be apparent that the wire may be introduced to the device and the completed shank removed by any suitable or desired means.

Having thus described my invention, what I claim as new and desire to secure by Letters Patent of the United States is:

1. A device of the class described having, in combination, a stationary former, bending tools for shaping a wire about the former, a tool for bending the ends of the eye so formed into alignment with each other, and a twisting tool for bending part of the aligned ends into a plane at right angles to the plane of the eye.

2. A device of the class described having, in combination, coöoperating tools for forming a button shank having an eye and oppositely extending feet in the plane of the eye, means for holding the center portion of the feet in the plane of the eye, and a single tool for bending part of both of the feet in opposite directions and at right angles to the plane of the eye.

3. A device of the class described having, in combination, coöoperating tools operating successively in separate steps to form an eye having oppositely extending ends in the plane of the eye, means for maintaining the center portion of said ends in the plane of

the eye, and a tool arranged to operate subsequently to the formation of the eye for bending part of each end in opposite directions at right angles to the plane of the 5 eye.

4. A device of the class described having, in combination, coöperating tools movable toward a common center to form an eye with outwardly extending ends, and another 10 tool arranged to turn about a radially disposed axis to bend the ends of the eye simultaneously in opposite directions.

5. A device of the class described having, in combination, coöperating tools movable 15 radially toward a common center to form an eye with outwardly extending feet and to clamp the part of the feet adjacent to the eye, and another tool arranged to turn about an axis disposed at right angles to 20 the clamped feet of the eye and bend their ends in opposite directions out of the plane of the eye.

6. A device of the class described having, in combination, a stationary tool holder 25 having a plurality of bending tools shaped to perform a series of different operations on a piece of wire and being movable in converging paths, and an oscillatory actuator having a separate cam for operating 30 each of said tools.

7. A device of the class described having, in combination, a tool holder having a former and a plurality of tools movable 35 toward the former to form an eye about it and to clamp the eye so formed, an actuating plate cut away at its center to receive the tool holder and having cams in its inner

edge for operating the tools successively and a rotatable end bending device movable with one of the bending tools. 40

8. A device of the class described having, in combination, a tool holder having a plurality of bending tools movably mounted therein with their outer ends projecting beyond the periphery of the holder, and an 45 actuating device surrounding the holder and tools having cam surface for causing the tools to operate when the tool holder and actuating device are moved relatively.

9. Mechanism for operating on an eye 50 with oppositely disposed alined feet, including means shaped to engage and clamp the center portion of the feet adjacent to the eye, and means movable relatively to the clamping means and transversely to the 55 plane of the eye for bending the outer portion of each of the feet.

10. Mechanism for operating on an eye with oppositely disposed alined feet, including a spindle having a slot in its end, 60 and a sleeve rotatable upon the spindle and having projecting shoulders on its end extending flush with the end of the spindle and arranged to engage the ends of a wire held in the slot of the spindle and bend 65 them about the cylindrical surface of the spindle end.

In testimony whereof I have signed my name to this specification in the presence of two subscribing witnesses.

FRANKLIN G. NEUBERTH.
